UNITED STATES PATENT OFFICE.

JOHN GLEN, OF BROOKLYN, NEW YORK.

DESIGN FOR A PRINTED FABRIC.

SPECIFICATION forming part of Design No. 13,112, dated August 1, 1882.

Application filed June 9, 1882. Term of patent 3½ years.

To all whom it may concern:

Be it known that I, JOHN GLEN, of Brooklyn, in the county of Kings and State of New York, have invented a new and original Design 5 for Printed Fabrics; and I do hereby declare that the following specification, taken in connection with the accompanying illustration, forming a part of the same, is a full, clear, and exact description thereof.

10 My design relates particularly to printed fabrics known as "calicos," although it is equally applicable to silks, woolens, and other fabrics, either printed or woven.

15 It consists in the representation of a collection of leaves and flowers, as will hereinafter appear.

Referring to the illustration, A represents a group of leaves, which are combined with a collection of flowers, B, the stems of which also 20 bear buds b, although these buds may be

omitted, if desired. The grouped leaves and flowers are repeated upon the surface of the fabric to form the pattern.

The fabric may be produced in any preferred variety or combination of colors for giving to 25 the design a desirable effect.

What I claim, and desire to secure by Letters Patent, is—

1. The design for printed and other fabrics, consisting of groups of leaves and flowers, arranged substantially as described and shown. 30

2. The design for printed and other fabrics, consisting of groups of leaves, flowers, and buds, arranged substantially as described and shown.

JOHN GLEN.
